UNITED STATES PATENT OFFICE.

BENJAMIN W. MORRIS AND WILLIS H. RODGERS, OF CIRCLEVILLE, OHIO.

WHIP-SOCKET.

SPECIFICATION forming part of Letters Patent No. 288,721, dated November 20, 1883.

Application filed February 14, 1883. (No model.)

To all whom it may concern:

Be it known that we, BENJAMIN W. MORRIS and WILLIS H. RODGERS, of Circleville, in the county of Pickaway and State of Ohio, have 5 invented certain new and useful Improvements in Whip-Sockets; and we do hereby declare the following to be a full, clear, and exact description of the invention, such as will enable others skilled in the art to which it pertains 10 to make and use it, reference being had to the accompanying drawings, which form part of this specification.

Our invention relates to an improvement in whip-sockets; and it consists in the combination of a slotted holder or socket and ratchet-ring, suitable spring-actuated locking devices, and a lock for locking the ring in position, so that the whip cannot be removed from the socket.

20 The object of our invention is to provide a means for locking the whip in the socket when the vehicle is left standing for a short time, so that the whip cannot be stolen during the owner's or driver's absence.

25 Figure 1 is a vertical section of our invention complete. Fig. 2 is a horizontal cross-section of the same. Fig. 3 is a side elevation of the socket complete.

30 A represents a suitable whip-socket, which has placed in its bottom the conical spring-receiver or support B. This receiver or support is secured to the bottom of the socket and is intended to receive the butt of the whip and support it in position. This receiver is made elastic and conical, so as to 35 take a sufficient hold upon the butt of the whip, to prevent it from moving loosely around from the jarring of the vehicle. Placed in the upper portion of the socket is the ring C, 40 which has suitable ratchets, D, formed on its inner side, and a small fine ratchet, E, formed upon its bottom. This ring has connected to it the small knob or handle F, which projects through a horizontal slot, G, in the socket.

45 By means of this handle this ratchet-ring is made to turn or rotate in the socket any desired distance. Just below the ring is placed a small spring-lock of any kind, and the bolt of this lock is made to engage with the small 50 ratchets E on the under side of the ring. This bolt serves to lock the ring in place by engaging with the ratchets E, and thus prevents the ring from rotating. As the ratchets ex-

tend in the same direction, if the ring is once turned so as to open the locking devices, and the bolt of the lock is then left free to move, the ring can be readily moved back into position again, because the bolt slips idly over the ratchets, and when the ring is returned to place, it is automatically locked, and can 60 only be moved when the key is again applied to it. Fastened in the top of the socket are a number of spring-actuated locking devices, O, which extend down far enough to have their lower ends come inside of the ratchets 65 D, formed in the locking-ring. When these locking devices are left free to move, their lower ends can be forced outward by the passage of the butt of the whip, so that the butt can pass freely down. When, however, this 70 ring has been turned so that the ratchets D press against the lower ends of the spring-actuated locking devices, they are forced inward, so as to grasp the side of the whip tightly, and thus prevent the whip from being 75 pulled out of the socket. When the owner or the driver of a vehicle has to leave it for any length of time, in order to prevent the whip from being stolen during his absence he has but to catch hold of the knob and move 80 around the ring in the slot, when the whip will be automatically locked in place without the use of the key. When he returns, it will be necessary to use the key, so as to unlock the ring, and then, after the ring has been 85 moved, the whip can be freely removed and replaced at will.

Having thus described our invention, we claim—

The combination of the ring C, having 90 ratchets formed in its inner edge to move the springs O, and having a ratchet, E, formed on its under side, and provided with a knob or handle F, with a lock having its bolt beveled at its upper edge, so that the ring can 95 be freely closed, but cannot be opened without the help of the key, substantially as set forth.

In testimony whereof we affix our signatures in presence of two witnesses.

BENJAMIN WEST MORRIS.
WILLIS H. RODGERS.
